(57) **CLAIM**

The ornamental design for a brooch as shown and described.

DESCRIPTION

FIG. 1 is a front, right-side, top perspective view of a brooch, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines shown illustrate portions of the brooch, and form no part of the claimed design.
